UNITED STATES PATENT OFFICE.

JOHN PAUL HANNA, OF CHICAGO, ILLINOIS.

DISPENSING PACKAGE.

Application filed February 14, 1924. Serial No. 692,670.

This invention relates generally to dispensing packages, and pertains particularly to an improved package of material in the nature of tablets or lozenges, such as medical 5 tablets.

The general purpose of the invention is the provision of such a package which may be manufactured at low cost, which will preserve the material against deterioration 10 and from excessive air or moisture contact and against soiling, which is particularly adapted for being carried on the person, as in the pocket, or in a hand bag, and which will facilitate the dispensing of the contained material in the quantities and at the 15 times desired.

Another object of the invention is the provision of such a package which is particularly adapted to minimize and simplify the 20 manipulations incident to dispensing the material, and which reduces to a minimum the amount of handling of the material requisite to remove it for its intended use.

Another object is the provision of such a 25 package possessing special attributes in preventing unintentional removal or discharge of the material.

Another object is the provision of such a package especially equipped to facilitate ascertaining of the amount of its contents.

Other and further objects of the invention will be pointed out hereinafter, indicated in the appended claims, or obvious upon an 35 understanding of the present disclosure.

For the purpose of this application I have 40 elected to disclose herein one form in which the invention may be embodied, but it is to be understood that such showing is made for the purpose of illustration only, and is not to be accorded the effect of limiting what I purport to secure, short of the true and 45 most comprehensive scope of the invention in the art.

In the accompanying drawing forming 50 part of this specification,

Fig. 1 is a perspective view of an illustrative package, showing the cover removed;

Fig. 2 is a longitudinal section of the package with the cover in place;

Fig. 3 is a top view with the cover removed; and

Fig. 4 is a detail in the nature of a longitudinal section of a slightly modified form.

The nature of the invention will best be 55 understood by reference to this illustrative form in detail, the various parts thereof be-

ing designated in the drawing by reference characters. Let it be understood that the reference numeral 15 designates the body portion of a container which is of generally 60 cylindrical, tubular form. This preferably may be constructed of suitable light sheet material, such as very light metal, celluloid, or others having the necessary strength and stability. The lower end of this body member 65 is closed in suitable fashion by a bottom 16 which is retained securely in place. At its upper end the body portion carries a retaining member 17 secured at one end to a longitudinal extension 18 on the wall of 70 the body member, which retaining member extends across the major portion of the bore of the body member. Throughout most of its perimeter this retaining member is spaced above the end of the body member 75 by a distance which is approximately the thickness of one of the tablets or other articles for which the container is designed, so that the articles may be engaged at opposite portions of their peripheries. Its transverse 80 width is preferably slightly less than the width of the bore of the body member. Approximately coaxially with the bore of the body member, the retaining member 17 is formed with an aperture 19 which may afford a seat for the purpose hereinafter referred to. A cover cap 20 is arranged to fit upon the upper end of the body 15 to close the same and house the retaining member 17. The body member 15 may be provided 85 with a narrow longitudinal slot 21 which is covered with a sheet 22 of transparent material.

In the body member 15 is disposed the material to be dispensed, in the form of a 90 number of tablets 24, which conform to the cross-sectional shape of the body member and are of such size as to slide freely therethrough and be retained thereby in approximately coaxial relationship. Between the 95 lowermost of these tablets and the bottom closure 16 is interposed a light follower spring 25 which is extensible for the full length of the body portion and tends to urge the tablets toward the retaining member 17. In the normal manufacture of the package, the tablets are inserted from the bottom preceding the placing of the spring 25 and affixing of the bottom closure 16. As a means for determining the number of tablets remaining in the package at any time, all, or those near the bottom, may be pro-

vided with distinctive markings, such as numerals corresponding to their original order in the package. These markings may be formed on their peripheries, as illustrated, or upon their end faces as shown in Fig. 8, or otherwise associated with them so as to be visible on the uppermost tablet when the cover is removed or through a transparent window 20^a in the same.

10. In most instances the end surfaces of tablets such as medicinal tablets, etc., are of dome or spherical contour. Consequently, the pressure from the spring 25 transmitted to the uppermost tablet will tend to seat a portion of its spherical surface in the axial seat afforded by the aperture 19. This co-operates to prevent unintentional dislodgment of the tablet from under the retaining member 17. The uppermost tablet may be 15 withdrawn, however, after the cap 20 is removed, by engaging it laterally with the fingers at opposite sides of the retaining member 17 and withdrawing it from under the latter, whereupon the subjacent tablet moves into engagement with the retaining member.

I have found that the arrangement permitting withdrawal of the tablet by lateral engagement is of distinct advantage in the dispensing of material such as the pressed tablets for which this package is particularly designed. It not only permits a grasp of the tablet which is natural and tends to prevent its being dropped, but it enables the article being moved much more positively than is possible where merely an engagement of the top surface is depended upon, and with less likelihood of soiling. Furthermore, it permits the retaining contact of the retaining member with portions of the tablet away from the margins thereof, thus tending to prevent crumbling or chipping of their marginal portions as the tablets are shifted into contact with the retaining member. With the cover 20 in place, the tablets are fully protected, and the contents may be inspected through the slot 21. While the aperture 19 has the added utility of permitting inspection of the end numeral on the uppermost tablet, the centering and retaining function of the seat may be obtained by forming the retaining member in other fashion, as with the seat depression 26 illustrated in Fig. 4. Disengagement of the domed portion of the tablet from the seat is permitted by the yieldable support of the subjacent tablet.

While, by provision of a detachable and replaceable bottom cover, the container is adaptable to refilling, the construction affords of such simplicity and economy that it may be employed as a merchandising package, not designed for refilling. Because of its secure retention of the contained tablets against accidental spilling, in conjunction with the readiness of intentional removal of

them which it permits, the package is of particular utility for carrying material in the pocket or in a purse or lady's hand bag.

I claim:

1. A package comprising the combination of a tubular body portion, a stack of tablets therein, a retaining member at one end of the body portion disposed to contact the outer end of the uppermost tablet, said retaining member being of less width than the tablets and spaced from the end of the body member to permit lateral withdrawal of a tablet between them, a removable cover for housing the retaining member and closing the end of the tube, and a follower spring arranged to urge tablets toward the retaining member.

2. A package comprising the combination of a tubular body member, a series of tablets movable coaxially therein, a retaining member mounted at one end of the body member and extending transversely of its bore for contact with the end tablet, said retaining member being of less width than the tablets so that diametrically opposite marginal portions of the latter project laterally beyond it, and an extension spring at the other end of the body member for urging the tablets toward the retaining member.

3. In a package, the combination of a tubular body member for reception of tablets, a retaining member at one end of the body member extended across the bore thereof but of less width than said bore, said retaining member being provided with an aperture on the axis of the bore, a removable cover for enclosing the retaining member and adjacent end of the body member, and a follower spring for moving tablets through the bore toward the retaining member.

4. A packaging device comprising the combination of a tubular body member, a retaining member mounted at one end of the body member and extending transversely of the bore thereof, said retaining member being spaced apart from the body member throughout the major portion of its perimeter, to permit engagement of articles between them, a movable cover for the slot, and a follower spring for moving articles through the body member toward the retaining member.

5. A packaging device comprising the combination of a tubular body member, a retaining member mounted to extend across one end of the body member, said retaining member being spaced apart from said end of the body member at opposite sides to permit digital engagement of an article between them, and means for moving articles through the body member toward the retaining member.

In testimony whereof I have hereunto subscribed my name.

JOHN PAUL HANNA.
